UNITED STATES PATENT OFFICE.

WALDEMAR DYRSSEN, OF NEW YORK, N. Y.

REGULATOR FOR FURNACE-ELECTRODES.

1,399,852.

Specification of Letters Patent. Patented Dec. 13, 1921.

Application filed December 12, 1919. Serial No. 344,324.

To all whom it may concern:

Be it known that I, WALDEMAR DYRSSEN, a subject of the King of Sweden, residing in the city, county, and State of New York, have invented certain new and useful Improvements in Regulators for Furnace-Electrodes, of which the following is a specification.

This invention refers to hoisting and regulating mechanism especially applicable for raising and lowering the electrodes in electric furnaces. Certain types of electric furnaces have vertical electrodes, usually three in number, which weigh approximately one ton each. Arcs are struck between these electrodes and the material on the hearth of the furnace which is melted or kept molten by the heat of the arcs. The amount of current flowing through the electrodes is regulated by lifting or lowering the electrodes, thus decreasing or increasing the resistance of the arcs. This regulation takes place at frequent intervals during the entire operation of the furnace. It is often necessary to rapidly raise or lower the electrodes several feet so that the furnace may be charged or discharged. In some devices used in this connection, an electric motor is caused to operate until the electrode is lowered to the proper point or raised to the proper point. The tendency in such a case is for the motor to overrun in either direction, thus the electrode floats up and down, never giving the exact regulation required.

With the improved apparatus herein shown the feed regulation is made intermittent and the electrode can be adjusted to the exact position desired and if a change takes place in the furnace during intervals of rest, so that regulation becomes unnecessary, the movement of the electrode does not take place and the regulation on the whole is better. In electric furnaces using three electrodes and three-phase electric current, it is important that the lifting or lowering movement of electrodes takes place one at a time and not two or three at a time. If the movement of the charge in the furnace causes a short circuit and a surge of current, it is important to be able to lift all the electrodes quickly, as with three-phase current, the arcs are interdependent and the lengthening of one arc will assist to prevent the rush of current through another. It is preferable that the small intermittent movements of the electrodes be accomplished

automatically and it is desirable to be able to change rapidly from automatic to non-automatic control.

One of the objects of my invention is to provide an automatic mechanism for raising and lowering electrodes according to variations in the heating current passing through the electrodes. Another object is to provide automatic means for intermittently raising and lowering the electrodes successively. A further object is to provide mechanism whereby the electrodes may be raised or lowered automatically at a slow rate of speed according to fluctuations of the power current, and means whereby they may be raised and lowered rapidly under the manual control of an operator. A still further object is to provide mechanism for automatically adjusting the electrodes in combination with manually controlled mechanism for rapidly moving the electrodes, these separate devices being interlocked so that it is impossible for an operator to effect the rapid movement of the electrodes without first disconnecting the devices which perform the automatic regulation. Another object is to organize the various elements described herein so they will effectively perform their various functions. Other objects will be apparent from the following specification and the appended claims when read in connection with the accompanying drawings in which—

Figure 1 is a view illustrating in vertical section a typical form of electric furnace equipped with my improved regulating mechanism;

Fig. 2 is a horizontal section on the line 2—2 of Fig. 1, showing the general arrangement of hoisting apparatus arranged to move the electrodes of a furnace having three electrodes;

Fig. 3 is an enlarged view in plan illustrating certain details of construction and arrangement;

Fig. 4 is a vertical section on the line 4—4 of Fig. 3 showing the selective means which determine the direction in which the electrode is adjusted;

Fig. 5 is a circuit diagram illustrating the arrangement of the electrically operated controls.

In the drawings a typical form of electric furnace 1 is provided with electrodes 2 each of which are carried on a vertically adjustable bracket 3 arranged to slide up and down

on the uprights 4. Each bracket 3 is connected by means of a cable 5 which passes over a sheave 6 supported at the top of the upright, with a winding drum 7 which is secured to a shaft 8 secured in bearings 9 supported on a suitable base 10. The mechanism for moving each of the electrodes 2 is identical and therefore a detailed description of one will suffice for the three.

10 A worm wheel 11 is secured to the drum shaft 8 and is arranged to be driven by a worm 12 carried by a shaft 13 which is supported in suitable bearings 14 carried by the base 10. This shaft has rigidly secured thereto a ratchet wheel 15 and a beveled gear 16 by means of which it may be driven either continuously or intermittently as hereinafter described.

15 A main drive shaft 17 supported in suitable bearings 18 is driven through gears 19 and 20 by an electric motor 21. This shaft 17 is common to the three secondary shafts 13. Loosely mounted on the shaft 17, adjacent bearings 18, are beveled gearings 22 and 23 each having a clutch face 24 and 25 formed thereon and arranged to co-operate with a clutch member 26 which is splined on the shaft 17 and arranged to be moved into engagement with either of the gears 22 and 23 by means of a clutch lever 27 secured to a shaft 28 journaled in a suitable fixed bracket. This arrangement permits of the rapid vertical adjustment of the electrodes in either direction according to which gear is engaged by the clutch member 26.

20 For effecting the slow automatic vertical adjustment of the electrodes in either direction I provide an oscillating frame 29, Fig. 4, which is fulcrumed on the shaft 13 and arranged to be rocked by a crank 30 secured to the shaft 17 by means of a connecting link 31. This oscillating frame carries a double acting feed dog 32 having teeth 33 and 34, the dog being pivoted on a stud 35 secured 45 to the frame and having a tail 36 extending upwardly therefrom. The frame 29 supports a pair of solenoids 37 and 38 which are arranged so that the movement of the core 39 thereof will move the tail of the dog 50 so as to cause either of the teeth 33 or 34 to co-act with the ratchet 15 thereby providing selective means whereby the shaft 13 can be moved in opposite directions so that the electrodes will be either raised or lowered by the cable attached to the drum 7.

25 To automatically control the direction of the vertical adjustment of the electrodes, I have provided means whereby either solenoids 37 or 38 can be energized according to whether a current of comparative high or low strength is flowing through the particular electrode controlled by said solenoids.

30 Referring to Fig. 5, I provide a secondary coil 39 of a transformer 40 which receives its induced current from the feed wire 41

supplying one of the electrodes 2. The current from coil 39 excites an ammeter 43 which in turn actuates a switch 42. When the current flowing through feed wire 41 drops, switch 42 will make contact with point 44 thereby closing a local circuit and energizing the solenoids 38 and causing the ratchet to be turned in the direction of the arrow in Fig. 4, so that the drum 7 will be turned to lower the electrode, and thereby decrease the resistance of the arc. In similar manner when the current in feed wire 41 becomes excessive, the ammeter 43 will move the switch 42 into contact with point 45 and thereby energize solenoid 37 which will cause the feed dog to be moved so as to actuate the ratchet in the opposite direction thereby turning the drum so as to raise the electrode and increase the resistance of the arc.

35 The current for energizing solenoids 37 and 38 is supplied by feed wires 46 and 47 and these solenoids are in a circuit including wires 48 and 49, a switch 50, wires 51 and 51^a and 52 and 53, the switch 42, wires 54, 55 and 56. The wires 48 and 55 serve as branch feeders for each of the units A, B and C which control the different electrodes. Each unit is wired up in the same manner as the one here described and the description of one will apply to each unit, except it is to be noted that as shown in the diagram the contact making ammeters 43 for the units B and C are actuated by a current induced by the transformers 59 and 60 respectively associated with the electrode feed wires 61 and 71. The circuit of motor 21 is controlled by double pole switch 80 connected across the feed wires 46 and 47.

40 Current for the electrodes is furnished by a suitable three-phase dynamo 100 through transformer 101 and wires 41, 61 and 71 and a main gang-switch 90 is provided to control the flow of current therethrough.

45 In order to make it impossible for the operator to throw the clutch 26 while the automatic feed is being effected by the ratchet 15, I have provided means whereby the switch 50 controlling a supply of current to the solenoids 37 and 38 are interlocked with the lever 27 which operates the clutch. This interlocking arrangement is illustrated in Fig. 3 where it will be seen that the shaft 28 to which the clutch lever 27 is secured has fastened thereto a sector 81 provided with a notch 82, which is engaged by a spring pressed latch 83 arranged to be moved by the switch lever 50. When the switch lever is in closed position it engages contact 49^a thereby closing the circuit from feed wire 47 at this point for either of the solenoids 37 or 38. In this closed position the clutch lever 27 cannot be rocked because of the engagement between the latch 83 and the notch 82 in the sector 81, hence it is impossible to 130

throw the clutch to high speed position at the same time the solenoids are connected for feeding the electrodes automatically.

When using a three-phase current for the electrodes it is desirable that the automatic feed be so effected that no two electrodes are moved at the same time and therefore, the cranks 30 which operate the different electrodes, which in the case illustrated, are 10 three in number, are set at an angular distance of 120 degrees apart, as shown in dotted lines in Fig. 4. Therefore, as the shaft 17 rotates, one electrode will be feeding while the oscillating frames for the other 15 two electrodes are on their backward or inactive strokes.

In operation assuming the electrodes to be at the high position, the switch 80 is first closed to start the motor 21 and the lever 27 is thrown so as to shift the clutch into 20 engagement with the gear 22. This will cause the shaft 13 to be rotated clockwise as shown in Fig. 4, thereby turning the drum 7 in the proper direction for paying off 25 cable so as to lower the electrode connected therewith, it being understood that the switches 50 must first be opened to permit the clutch lever to be thrown. After the electrodes have been lowered approximately 30 to the desired position the clutch 26 will be disengaged and the main switch 90 for supplying current to the electrodes will be closed, then the switches 50 for cutting in the automatic feed will be 35 closed. Variations in current flowing to the electrodes will then actuate the various contact making ammeters 43 thereby moving the switches 42 and closing the circuit for either of the solenoids 37 or 38 according to 40 whether the said electrode current is above or below a determined strength. This will cause the ratchets 15 to be turned in a direction determined by the solenoid energized thereby raising or lowering the particular 45 electrode as the case may be. The parts are so proportioned that when the drums 50 7 are driven at high speed through the gears 22 or 23 and 16 these drums will rotate approximately one revolution per minute which will result in moving the electrodes at the rate of about thirty inches per minute. When the automatic feed is in operation the electrodes are moved at a much slower rate, there being 55 12 teeth in ratchet 15 and said ratchet driven by the cranks 30 which in turn are driven through the reduction bevel gearing 30^a as shown in Fig. 3. These parts are so proportioned that at this time the electrodes 60 are moved at the rate of five inches per minute or one-twelfth of an inch per second or per stroke of the connecting rod 31. Of course the parts may be proportioned differently so as to effect different rates of feed, 65 but experience shows this rate of adjust-

ment to be an effective one. If no regulation is required due to an even flow of current to the electrodes and general favorable conditions inside of the furnace, the electrodes will remain at rest, it being understood that the feed dog 32 at such time will be held in the central position shown in Fig. 4 by means of the centering springs 36^a, it being clear that at such times the electrodes cannot move downward by gravity due to 70 the self locking action between the worm 12 and its mating wheel 11. In the event of the charge in the furnace shifting or other conditions effecting a short circuit, it is necessary to rapidly raise the electrodes 75 and at such times the switches 50 will be opened and clutches 26 operated so as to engage the gears 23 thereby rapidly turning the drums 7 in the proper direction to raise the electrodes. 80

The apparatus herein disclosed is a marked improvement over the devices heretofore employed and by its use a more even regulation of the temperature in the furnace is obtained and consequently the character 90 of the metal treated is improved.

As it is clear that changes in arrangement and construction may be made by those skilled in the art without departing from the invention it is intended that all 95 matter described herein and shown on the accompanying drawings shall be interpreted in an illustrative rather than a limiting sense.

What I claim is:

100

1. An electric furnace having a plurality of electrodes and automatic means for intermittently moving the electrodes successively to vary the resistance of the arcs at different times so that no two electrodes are moved 105 simultaneously.

2. An electric furnace having a plurality of electrodes and automatic means for intermittently moving the electrodes in sequence at different times to control the strength of 110 current flowing to the electrodes.

3. In combination with an electric furnace, a plurality of electrodes, drums having cables secured thereto for moving said electrodes, a motor, connections between 115 said motor and said drums for intermittently moving said drums at different times so that no two electrodes are moved simultaneously.

4. In combination with an electric furnace, a plurality of electrodes, drums having cables secured thereto for moving said electrodes, a motor, connections between 120 said motor and said drums for intermittently moving said drums at different times 125 so that no two electrodes are moved simultaneously and means controlled by the strength of current flowing through the electrodes for controlling the direction in which said drums are turned so that as the 130

electrode-current diminishes the electrodes are lowered and as said current increases the electrodes are raised.

5. In combination with an electric furnace, a drum having a cable connected thereto for moving an electrode, a motor for driving said drum, and connections between said motor and said drum whereby the drum can be driven continuously at a 10 high speed or intermittently at a slow speed.

6. In combination with an electric furnace, a drum having a cable connected thereto for moving an electrode, a motor for driving said drum, and connections between said motor and said drum whereby the drum can be driven continuously at a high speed or intermittently at a slow speed, and means controlled by the current flowing 15 to the electrode for controlling the direction in which said drum is intermittently moved.

7. In combination with an electric furnace, a drum having a cable connected thereto for moving an electrode, a main-drive shaft having reversing gearing carried thereon, a secondary shaft connected by said gearing to said main shaft, a reversing clutch normally disengaged from said reversing gearing, means for moving said clutch to effect the rapid rotation of said drum in either direction, a ratchet wheel secured to said secondary shaft and means carried by the main shaft for actuating said 30 ratchet wheel.

8. In combination with an electric furnace, a drum having a cable connected thereto for moving an electrode, a main-drive shaft having reversing gearing carried 40 thereon, a secondary shaft connected by said gearing to said main shaft, a reversing clutch normally disengaged from said reversing gearing, means for moving said clutch to effect the rapid rotation of said drum in either direction, a ratchet wheel secured to said secondary shaft and a feed 45 dog normally out of engagement with said ratchet, means for moving said feed dog into operative engagement with said ratchet and means actuated by the main shaft for moving said feed dog to effect the movement of said ratchet.

9. In an electric furnace, a drum for moving an electrode, a shaft having a gear thereon for turning said drum, a ratchet wheel secured to said shaft, an oscillating bracket supported by said shaft and carrying a feed dog arranged to move said ratchet wheel in opposite directions, a pair of solenoids carried by said oscillating frame controlling the direction in which said feed dog moves said ratchet, said solenoids being in circuits controlled by a relay which is actuated by variations in the strength of

65 current flowing to the electrode, means including a normally disengaged clutch for rotating said shaft at a high speed and means associated therewith for breaking the circuit to said solenoids to prevent the operation of said feed dog when said clutch is 70 engaged to drive said shaft.

10. In combination with an electric furnace, a plurality of electrodes, drums having cables connected thereto for moving said electrodes, secondary shafts for turning 75 said drums, ratchet wheels secured to said shafts, oscillating frames supported on said shafts, feed dogs carried by said oscillating frames, electro-magnetic means for moving said feed dogs to position to co-act with said 80 ratchet wheels, cranks set at different angular positions for rocking said frames in such sequence and direction that no two electrodes will be either raised or lowered simultaneously and a main shaft for driving 85 said cranks.

11. In combination with an electric furnace, a drum having a cable connected thereto for moving an electrode, a secondary shaft for driving said drum, a main shaft, 90 reversing gearing connecting said shafts, a reversing clutch on said main shaft, a lever for operating said clutch, a ratchet wheel secured to said secondary shaft, an oscillating frame carrying a feed dog adapted to 95 co-act with said ratchet wheel, a crank driven by said main shaft for oscillating said frame, solenoids for moving said feed dog to operative position, a switch for controlling the circuit of said solenoid and 100 means associated with said switch whereby the said clutch lever is interlocked with said switch so that it cannot be actuated until after the circuit of said solenoids has been broken by the switch.

12. In combination with an electric furnace, a drum having a cable connected thereto for moving an electrode, a main drive shaft, reversing gearing and a clutch carried thereby, a secondary shaft having a 110 ratchet wheel secured thereto, an oscillating frame carrying a feed dog arranged to co-act with said ratchet wheel, solenoids for moving said feed dog to operative position, a relay actuated by the current flowing 115 through the electrode and arranged to make a circuit through one of said solenoids when the electrode current drops and through the other of said solenoids when said electrode current raises to respectively lower or raise 120 said electrode, means for moving the clutch on the main shaft and a switch interlocked therewith for breaking the circuit to said solenoids when the clutch is actuated.

125 In witness whereof, I have hereunto signed my name.

WALDEMAR DYRSSEN.
